(57) **CLAIM**

The ornamental design for a tremolo, as shown and described.

DESCRIPTION

FIG. 1 is a top view of an ornamental design for a tremolo; FIG. 2 is a top view of the ornamental design for the tremolo;

FIG. 3 is a bottom view of the ornamental design for the tremolo;

FIG. 4 is a left view of the ornamental design for the tremolo;

FIG. 5 is a right view of the ornamental design for the tremolo;

FIG. 6 is a front view of the ornamental design for the tremolo; and,

FIG. 7 is a rear view of the ornamental design for the tremolo.

The features shown in broken lines represent the portions of the tremolo that form no part of the claimed design.
